HEAT EXCHANGERS

Curt Fredrik Rosenblad, Sodertalje, Sweden, assignor to Aktiebolaget Rosenblads Patenter, Sodertalje, Sweden, a corporation of Sweden

Application February 4, 1937, Serial No. 124,113
In Sweden February 1, 1936

4 Claims. (Cl. 257—245)

This invention refers to heat exchangers of the spiral sheet metal type, i. e. heat exchangers having the heat transmitting surfaces made of one or more metal sheets wound to spirals, and forming walls of the channels for the flowing media between which heat is to be exchanged.

The chief purpose of this invention is to render such apparatus more resistive to shocks and other stresses and strains, without increasing the quantity of material used and the weight of the apparatus. For the same resistance the heat exchanger in accordance with this invention may be constructed with a smaller quantity of material and have a lesser weight than that of ordinary apparatus.

Another purpose of this invention is to render it possible to reduce the thickness of the spiral metal sheets, without impairing the function of the apparatus and without reducing its resist-
ance to shocks and strains. For the heat transmission, it is desirable to reduce the thickness of the sheet metal as much as possible, but heretofore such reduction could not be carried very far without diminishing the resistance of the apparatus. In such spiral heat exchangers it is absolutely necessary, that the metal sheets are not deformed, because otherwise the function of the apparatus will be seriously impaired and the resistance to the flow will increase to values too high for practical operation, rendering the drop of pressure in the apparatus exceeding high.

It was also proposed to use distance pieces welded to the metal sheets, but the mounting of such pieces, being several thousand in big apparatus, implies a great cost and because the welding requires a certain minimum thickness of the metal sheet, the thickness of the metal sheets could not heretofore be reduced as much as desired. The welded spots or seams are also liable to be more easily attacked by corrosion.

A further purpose of this invention is to avoid welding as much as possible so as to render the heat exchanger more resistive to corrosion and chemical action.

A further object of this invention is to simplify the manufacture and the mounting of heat exchangers made of spiral metal sheets.

Other objects will be evident from the following specification and claims.

Some embodiments of the invention are illus-
trated in the annexed drawing.

Fig. 1 is a cross section through an apparatus in accordance with this invention, taken on the line I—I in Fig. 2.

Fig. 2 shows an axial section on the line II—II in Fig. 1.

Figs. 3 and 4 show details of axial sections through other embodiments, in which both of the spiral metal sheets are corrugated.

Referring now to Figs. 1 and 2 of the drawing, the spiral heat exchanger has two spiral metal sheets 1 and 2, of which the sheet 1 is smooth, while the sheet 2 is corrugated in such manner that the corrugations extend in the peripheral direction of the spiral, i. e. their longitudinal direction is at right angles to the axis of the spiral. The cold medium is supplied through the pipe 3 and is drawn off through the pipe 4 after having passed through the spiral channel 8. 15 Analogously, the hot medium enters through the pipe 5, flows through the channel 7 and is drawn off through the pipe 6.

In the axial direction the channels 7 and 8 are closed by strips 9 in well-known manner, for instance, in accordance with U. S. Patents No. 2,011,201 or 1,930,879.

It is evident that the metal sheet 2 is rendered more rigid and resistive to shocks and pressure as a result of the corrugation, while the spiral 25 flow in the peripheral direction is entirely unrestricted. For this reason, the efficiency of the heat transmission is very high.

Fig. 3 shows an embodiment in which the two metal sheets are both corrugated, their corrugations being displaced somewhat in relation to each other. It is easily seen from the figure that the surface of heat transmission per unit of volume is increased in this apparatus, as compared with the ordinary sheet metal apparatus 35 having smooth noncorrugated metal sheets.

Fig. 4 shows an embodiment having the two metal sheets 1, 2 corrugated with corrugations having different heights (or amplitudes).

It is to be observed that in any of the embodiments shown all the sheet metal plates abut against each other on one or both sides, inasmuch as the top edges of the corrugations are in contact throughout their entire length with the adjacent sheet metal plate. Thus, the rigidity and the ability to resist shocks and other stresses and strains are very much increased, without any increase in the weight of the apparatus, or the apparatus may be built of thinner sheet metal, while still retaining sufficient strength.

By the term "corrugated" as used herein, I mean a surface having alternate ridges and grooves without limitation to their particular shape. While I have shown and described several more or less specific embodiments of my inven- 55

tion, it is to be understood that the scope of my invention is not to be limited thereby but is to be determined by the appended claims viewed in the light of the prior art.

5. What I claim is:

1. In a heat exchanger for indirect heat transmission between fluids, substantially parallel spiral walls of sheet metal forming therebetween spiral channels for flow of the fluids in spiral paths, at least one of said spiral walls being corrugated, the corrugations extending substantially parallel to the direction of flow, the crests of the corrugations abutting along substantially their entire length against the adjacent walls on both sides of said corrugated walls so that all said walls abut directly against each other.
2. In a heat exchanger for indirect heat transmission between fluids, substantially parallel spiral walls of sheet metal forming therebetween spiral channels for flow of the fluids in spiral paths, said spiral walls being corrugated, the corrugations extending substantially parallel to the direction of flow, all the corrugations being substantially uniform in shape and abutting against each other on both sides substantially along the entire length of their crests so that all said walls abut directly against each other.

3. In a heat exchanger for indirect heat transmission between fluids, in combination, two substantially parallel spiral walls of sheet metal forming therebetween spiral channels for flow of the fluids in spiral paths, one of said spiral walls being substantially smooth and the other being corrugated, the corrugations extending substantially parallel to the direction of flow and the crests of said corrugations abutting on both sides against adjacent turns of said smooth wall. 10

4. In a heat exchanger for indirect heat transmission between fluids, substantially parallel spiral walls of sheet metal forming therebetween spiral channels, for heat exchanging fluids to pass therethrough in spiral paths, said walls being 15 corrugated substantially in the direction of flow, in such manner that in adjacent metal sheets the corrugations have approximately the same pitch but a different amplitude, while those of said crests which are facing the same way abut 20 against each other substantially along their entire length to support each other, so that the windings of said metal sheets on both sides abut directly against adjacent windings. 25
